UNITED STATES PATENT OFFICE.

HARRY Y. NORWOOD, OF ROCHESTER, NEW YORK, ASSIGNOR TO TAYLOR INSTRUMENT COMPANIES, OF ROCHESTER, NEW YORK, A CORPORATION OF NEW YORK.

DESIGN FOR A THERMOMETER-SUPPORT.

54,352.

Specification for Design.

Patented Dec. 30, 1919.

Application filed April 23, 1919. Serial No. 292,183. Term of patent 14 years.

To all whom it may concern:

Be it known that I, HARRY Y. NORWOOD, a citizen of the United States, residing at Rochester, in the county of Monroe and State of New York, have invented a new, original, and ornamental Design for Thermometer-Supports, of which the accompanying drawing is a representation.

Figure 1 is a top plan view of a thermometer support showing my new design.

Fig. 2 is an elevation of the same.

I claim:

The ornamental design for a thermometer support, substantially as herein shown and described.

HARRY Y. NORWOOD.
